(57) **CLAIM**

We claim the ornamental design for plunger driver head for syringe pump, as shown and described.

DESCRIPTION

FIG. 1 is a perspective view of a plunger driver head for syringe pump.

FIG. 2 is a front elevation view of the plunger driver head for syringe pump.

FIG. 3 is a rear elevation view of the plunger driver head for syringe pump.

FIG. 4 is a side elevation view of the plunger driver head for syringe pump.

FIG. 5 is another side elevation view of the plunger driver head for syringe pump, from the side opposite that in FIG. 4.

FIG. 6 is a top plan view of the plunger driver head for syringe pump; and,

FIG. 7 is a bottom plan view of the plunger driver head for syringe pump.

The dashed broken lines depict portions of the plunger driver for syringe pump that form no part of the claimed design.
